UNITED STATES PATENT OFFICE

INGEMON MOE AND CHARLES A. SMITH, OF FERNDALE, MICHIGAN, ASSIGNORS TO LIPTAK FIRE-BRICK ARCH COMPANY, OF MEXICO, MISSOURI, A CORPORATION OF MINNESOTA

WATER-COOLED FURNACE ARCH

Application filed September 6, 1928. Serial No. 304,316.

This invention relates to fire arches and, more particularly to fire arches of the double suspension type, such as disclosed and broadly claimed in Letters Patent of the United States No. 1,326,752, granted to Michael Liptak of date December 30, 1919, and entitled "Furnace arch for boilers;" and it has for its chief object the provision of an improved means for cooling the arch by an arrangement of water tubes or parts incorporated therein and arranged or adapted to be arranged to preheat water for introduction into the boiler.

Generally stated, the invention consists of the novel construction, combinations and arrangement of parts hereinafter described and defined in the claims.

The invention is illustrated in the accompanying drawings, wherein like characters indicate like parts throughout the several views.

Referring to the drawings:

Fig. 1 is a view partly in vertical section and partly in diagram, showing the invention incorporated in a double suspension arch of the general type disclosed and claimed in the prior Liptak patent above identified, combined with an ignition arch of the type disclosed in the Strachota Patent 1,626,982, of date May 3, 1927, entitled "Fire arch structure;"

Fig. 2 is a transverse vertical section taken approximately on the line 2—2 of Fig. 1, the blocks of said arch being shown in full elevation;

Figs. 3, 4, 5, 6 and 7 are detail views showing blocks used in the construction of the arch illustrated in Fig. 1;

Fig. 8 is a view corresponding to Fig. 1, but illustrating a modified form of the arch, wherein the main arch and the ignition arch are designed as a continuous arch structure;

Fig. 2 is also illustrative of a section taken on the line 2—2 of Fig. 8;

The arch shown in Fig. 8 is made up of the blocks shown in detail in Figs. 4 to 7, inclusive, and also of blocks illustrated by the detail views Figs. 9 and 10, which show certain of the blocks in side elevation.

Referring first to the construction illustrated in Figs. 1 and 2:

The numeral 11 indicates the stoker hopper structure, which is customarily equipped with a gate, not shown, and which delivers the fuel onto an endless fuel carrier 12. The numeral 13 indicates flues and the numeral 14 a front water leg of a tubular boiler, which latter, as shown, is in communication with an underlying water drum 15, but might be otherwise connected.

The customary masonry of the furnace is well understood and is not here illustrated. The furnace arch, of course, occupies the usual position and spans the space between the sides of the furnace walls in front of and below the flues. The transverse main supporting arch beams 16, 17 and 18 are preferably heavy I-beams supported at their ends from the side walls of the furnace in a well known manner. A multiplicity of laterally spaced supplemental arch beams 19 are hung from the lower flanges of the I-beams 17 and 18 by means of hanger brackets 20. The front ends of the beams 19 are curved through 90° and then turned vertically upward. The supplemental beams 19 may be and preferably are made up of sections substantially as illustrated in the two prior patents above identified.

The main body of the double suspension arch is made up of upper or hanger blocks 21 (Fig. 3) and lower or under-surfacing blocks 22 (Fig. 4). The upper flanges of the blocks 21 are hung on the lower flanges of the supplemental beams 19, while the upper flanges of the lower blocks 22 are hung on and are slidably supported by the lower flanges of the upper blocks 21. As best shown in Fig. 2, the depending shoulders of the lower blocks 22 are cut down so as to form large longitudinal air channels extending through and longitudinally of the double suspension arch, and which channels afford spaces to receive water tubes 23. The curved or radial portion of the arch is made up of wedge-shaped upper blocks 24 and wedge-shaped lower blocks 25, which, in cross section, correspond in shape to the blocks 21 and 22, respectively. The blocks 24 are

hung on the curved portions of the flanges of the supplemental beams 19, while the upper flanges of the lower blocks 25 are hung on the lower flanges of the upper 5 wedge-shaped blocks 24. The vertically extended inner end portion of the double suspension arch is made up of the blocks 21 and 22 applied to the supplemental beams and connected together in the same manner as the 10 main arch-forming blocks, except that they are horizontally extended. These blocks, thus applied, have the tube passages so that the water tubes 23 are extended through the curved and through the vertical portion of 15 the arch. In the construction illustrated, the upper ends of the tubes 23 are connected to a water drum or header 26, while the other ends of said tubes are connected to a water drum or header 27. The water drum 27 may 20 be connected to a source of water supply, not shown, and the water drum 26, in one way or another, may be connected to the boiler, but, as shown, is connected indirectly thereto through a water pipe 28 that connects 25 the drums 15 and 26.

An apron wall 29, of refractory material, underlies the rear or inner ends of the lower tubes 13, and this is built directly upon cast supporting brackets 30, which, in turn, are 30 rigidly connected to and supported from the I-beam 18. The space between the top of the vertical inner end portion of the arch and the overlying apron wall 29 is filled in by filler blocks 31 that are notched so as to 35 clear the upper portions of the water tubes 23.

The ignition arch, which, as stated, is shown as of the type disclosed in the prior Strachota patent, is supported by heavy cast hanger brackets 32 that are anchored at their 40 upper ends to the I-beams 16 and support an outer insulating brick wall 33, an ignition arch proper 34, and filler blocks 35, the exact arrangement of which is important to the present case but is more fully disclosed in 45 the said Strachota prior patent.

Obviously, the upper blocks 21 will slide onto and off from the lower flanges of the beams 19, while the lower blocks 22 will slide onto and off from the lower flanges of said 50 upper blocks. It is important to note that the blocks that are hung on the vertically disposed inner ends of the beams 19 are extended high up and so close to the curtain wall 29 that the space can be filled in by a single 55 row of filler blocks 31. Also, it will be noted that the curtain wall 29 is supported entirely from the beam 18 through the shelf-forming brackets 30.

The arch just above described and particularly illustrated in Fig. 1 is of a general type or outline that may be designated as of standard contour. The water-circulating connections, including the tubes or pipes 23, are a part of the boiler water-circulating system. 60 The effect of placing the tubes or pipes 23

within the arch and between the upper and lower blocks is, first, to cool the arch and increase the life thereof and, second, to pre-heat the water before it is introduced into the boiler.

The system is so designed that it could generate some steam and, hence, can be used as a combined generator and feed water heater. The system of pipes should be so arranged that water would flow through them without pocketing of any steam that may be generated. The manner of applying the tubes in the arch is highly important and it will be noted that this is accomplished simply by forming the upper and lower blocks so that there will be sufficient clearance between them for the introduction of the tubes, and the said arch-forming blocks are of such form that the tubes may be omitted in certain structures, without requiring blocks of a different design.

The arches here illustrated are of the type well known to the trade as the Liptak double suspension arch. The arch illustrated in Fig. 8 is of a special curved design in which the main arch is continued to form the ignition arch and in which the water pipes or tubes run continuously through the main and ignition portions of the arch. In the structure illustrated in Fig. 8, the parts designated by the characters 11, 12, 13, 14, 15, 18, 20, 26, 28, 29 and 30 are identical with elements designated by the same numerals in the structure previously described. In this structure, the two main cross beams 17^a are located one higher than the other to adapt themselves to the curved formation of the arch, and the flanged beams 19^a, which carry the arch-forming blocks, are also curved or downwardly bent at the ignition end of the arch to form the ignition arch. Otherwise, the beam 19^a correspond to the beams 19 previously described. The combustion arch shown in this view, Fig. 8, is made up of the blocks 21, 22, 24, 25 and 31 previously described as being used in the arch of Fig. 1, but it also includes the additional blocks 32 and 33 shown in detail, respectively, in Figs. 9 and 10.

These blocks 32 and 33 have the same cross-section as the blocks 21 and 22, but they are made wedge-shaped to form that portion of the arch, Fig. 8, that blends the main arch into the ignition arch. The blocks of the arch Fig. 8, like the blocks of the previously described arch, are, as already indicated, so formed that there is ample clearance between the upper and lower blocks for the water pipes or tubes 23. Here attention is again called to the fact that Fig. 2 illustrates a cross-section of the arch illustrated in Fig. 8, as well as that of the arch illustrated in Fig. 1. So far as cooling of the arch and pre-heating of the water are concerned, the arch illustrated in Fig. 8 has all of the advantages

of the arch illustrated in Fig. 1, with the additional advantage that the ignition portion of the arch will be cooled and the heating effect on the water will be increased.

5 From the above description and statements made, it will be understood that the invention herein disclosed is capable of modifications as to details of construction and arrangement of parts, all within the scope of 70
10 the claims hereof.

It will be noted that the filler blocks 31, in longitudinal section, are wedge-shaped so that they will clear the brackets 30 and are formed adjacent their inner faces with upper standing shoulders that are adapted to form lap joints with the overlying curtain wall 29. These filler blocks may, therefore, be very readily replaced.

The upper pipes 23 can be placed in the 20 clearance space between the upper and lower arch-forming blocks, either with a refractory filling material of good heat-conducting capacity, or they can be used with no packing within the recess.

25 What we claim is:

1. A furnace arch comprising laterally spaced flanged metal beams and upper and lower arch-forming blocks, said upper blocks having relatively narrow depending T-shaped portions and said lower blocks having relatively narrow upwardly extended T-shaped portions slidably interlocked to the T-shaped portions of said upper blocks, said lower blocks having bodies being so 35 formed as to substantially space them from said upper blocks to form longitudinal channels, and water pipes located in said channels and extended through said arch, said water pipes being each interposed between 40 the point of meeting of two lower blocks and the lower face of an upper block.

2. A furnace arch comprising a plurality of interlocked upper and lower arch-forming blocks extended at the inner end of the 45 arch to form a substantially vertical inner end arch portion, a transverse beam located adjacent to said vertically extended arch portion but on the outer side thereof, brackets supported from said beam and projecting above the vertical inner end portion of said arch, a curtain wall supported by said brackets, and filler blocks supported on the upper inner end portion of said arch and closing the space between the same and the 55 overlying curtain wall, water pipes extended between the upper and lower blocks of said arch and through the vertically extended inner end portion thereof, and thence outward through the space between the inner end portion of said arch and the overlying curtain wall, the said filler blocks being notched to clear the upper portions of said water pipes.

3. A group of arch-forming blocks having interlocking engagement so that lower 60 blocks will be supported from upper blocks,

said lower blocks having body portions arranged in abutting relation and being so formed as to provide spaces below the lowermost portions of the upper blocks, said spaces being adapted to receive water pipes, and water pipes extended in the spaces between 70 said upper and lower blocks.

In testimony whereof we affix our signatures.

INGEMON MOE. 75
CHARLES A. SMITH.
